UNITED STATES PATENT OFFICE.

JOHN T. PRATT, OF TIPTONVILLE, TENNESSEE.

TILING BLOCK.

Application filed July 7, 1921. Serial No. 482,995.

To all whom it may concern:

Be it known that I, JOHN T. PRATT, a citizen of the United States, residing at Tiptonville, in the county of Lake and State 5 of Tennessee, have invented certain new and useful Improvements in Tiling Blocks; and I do hereby declare the following to be a full, clear, and exact description of the invention, such as will enable others skilled in 10 the art to which it appertains to make and use the same.

The invention relates to a tile or finishing block for walls.

An important object is to provide an article of this class which may have a metallic or equivalent backing type adapted to be fastened by nails or otherwise to a wall and which has a facing of plastic or molded material secured thereto.

Another object is to provide a novel, effective, cooperating and interlocking connection between the backing plate and the facing material of the particular construction hereinafter described.

Additional objects are to provide a novel means whereby the tile may interlock with each other and conceal their means of fastening; one in which heat necessary to the junction of the facing and backing may be substantially equally applied to both sides of the tile, and to provide a tile of the particular construction shown.

In accompanying drawings, one practical embodiment is illustrated, and therein:—

Figure 1 is a front elevation of a tile constructed in accordance with my invention;

Figure 2 is a horizontal sectional view through a plurality of the tile and a wall to which they are fastened; and

Figure 3 is a transverse sectional view through a portion of Figure 2.

Referring specially to the drawings, wherein like reference characters designate like or similar parts throughout the views, a backing or securing plate 4 is provided which is preferably of thin sheet metal, such as tin. At 5, the facing of the tile is shown. It will be noted that at one end and one side edge of the facing 5, the backing 4 projects beyond the same so as to form attaching flanges 6 and 7, through which nails 8 may be driven in order to secure the tile to a wall, conventionally suggested, at 9. The end wall and the side wall of the facing 5 adjacent to the attaching flanges 6 and 7, are beveled inwardly as at 10 so that the outer

wall of the facing 5 will project beyond the inner wall of said facing 5 and over said attaching flanges. The other side edge wall and end of the facing are beveled in the opposite direction at 11 to wall 9, so that the rear wall of the facing will project beyond the front wall of the facing.

It will be seen that the tiles are fastened against a wall by means of the nails 8. The adjacent walls at the longitudinal and end edges of the tile interlock, concealing the flanges 6 and 7 and attaching nails 8, by reason of beveling such walls at 10 and 11.

Facing 5 may be of any suitable material and in carrying out the invention, I may make the same of plastic or molded material. In order to form an interlocking connection between the facing and the plate 4, the backing at relatively close intervals is struck inwardly to provide relatively rough tubes or spurs 12 which embed in the backing 5 before hardening. Incidental to the provision of the spurs 12, openings 13 will be provided through the plate which are wider as 14, through the manufacturing process of the plate. Due to this construction, the molded or plastic material, before hardening, enters the openings 13 and spreads into the larger portion 14, so as to provide in effect, fastening heads on the plastic material or facing 5 as at 15, which are impossible through the openings 13 in a direction to release the facing 5.

When the tile is subjected to heat, incidental to molding or pressing the facing 5 from glass or vitreous material, the construction will enable the heat to be substantially equally applied to both sides of the tile.

Changes may be made within the spirit and scope of the invention as defined by appended claims.

What is claimed is:—

1. A tile having a backing substantially rectangular in shape, said backing having one side and one end wall beveled, said backing having the other side and end wall beveled opposite to the side and end wall first mentioned, and attaching flanges secured to and projecting beyond the backing at one side and one end thereof.

2. A tile having a backing plate, a facing, a projection extending from the backing plate embedded in the facing, said projection having an opening therethrough filled with the material of the backing, and said

opening being widened at a portion thereof for the purpose specified.

3. A tile having a backing plate, a facing, a fastening projection extending from the 5 backing plate embedded in the facing, said projection having an opening therethrough filled with the material of the backing, and said opening having an enlarged portion of the attaching face of the backing for the 10 purpose specified.

4. A tile having a backing plate provided with a plurality of projections, a facing in which said projections are embedded, said projections having openings there- 15 through filled with the material of the backing, and said plate and material in the openings being exposed in one side of the tile enabling heat to be applied to the back face.

of the facing to the same degree substantially as to the front face.

5. A tile having a facing, an attaching flange projecting beyond one side and one end wall thereof, the said side and end walls being deflected so that their inner edges are 25 farther from the adjacent marginal edges of the flange than their outer edges, and the other end and side walls of the facing being deflected substantially into parallelism to the side and end wall first mentioned.

In testimony whereof I affix my signature 30 in presence of two witnesses.

JOHN T. PRATT.
